UNITED STATES PATENT OFFICE.

JESSE D. LANGDON, OF WATERVILLE, WASHINGTON.

AUXILIARY VALVED-HEAD ATTACHMENT FOR INTERNAL-COMBUSTION MOTORS.

1,316,454.

Specification of Letters Patent. Patented Sept. 16, 1919.

Application filed November 4, 1918, Serial No. 128,464. Renewed March 10, 1919. Serial No. 281,793.

To all whom it may concern:

Be it known that I, JESSE D. LANGDON, a citizen of the United States, residing at Waterville, in the county of Douglas and 5 State of Washington, have invented certain new and useful Improvements in Auxiliary Valved-Head Attachments for Internal-Combustion Motors; and I do hereby declare the following to be a full, clear, and exact 10 description of the invention, such as will enable others skilled in the art to which it appertains to make and use the same.

My invention relates to an improved auxiliary valved head attachment for internal 15 combustion motors and the valve operating mechanisms therefor, and my primary aim is to provide novel mechanisms capable of efficient application to any of the motors now in use, or which may be built in motors here- 20 after manufactured, for raising the normal power curve of the motor.

A further aim is to provide auxiliary means for incorporating additional valves other than the valves ordinarily employed 25 in internal combustion motors, and to provide means for operating the ordinary valves and the additional valves and to also alter the functions of said valves as desired.

These and other aims and advantages of 30 my invention will more fully appear as the nature of the invention is more clearly understood from the following specification, the subject-matter of the claims, and the adopted views illustrated in the accompany- 35 ing drawings, in which:

Figure 1 is a side view, partly broken away and partly in section, of a combustion motor showing one method of applying my invention thereto, and

40 Fig. 2 is a view similar to Fig. 1 showing another method of applying my invention to a motor.

I desire to here state that for the sake of clearness and convenience in illustrating the 45 applications of my invention I have adopted only two of the various methods which I employ to accomplish the desired results, that I do not therefore restrict my invention to the exact details as herein shown and de-

50 scribed as my invention is capable of an extensive field of use, and that I may resort to alterations and variations therein as I may deem expedient to meet the exigencies

of the case without departing from the spirit of this invention or the scope of the 55 claims.

One of the methods by which I attain the desired results of my invention is illustrated in Fig. 1 of the drawings and wherein is shown that part of an ordinary combustion engine sufficient to show the application of my invention, and comprises the engine base 1, the engine shaft 2 having mounted thereon the fan belt pulley 3 and the gear 4 meshing with the gear 5 upon the end of 60 the cam shaft 6 provided with the intake valve operating cams 7 and the exhaust valve operating cams 8.

The cams 7 actuate the stems 9 of the intake valves 10 for controlling the fuel 70 charge in the fuel chambers 11 connected with the intake manifold 12, while the cams 8 operate the stems 13 of the exhaust valves 14 for controlling the passage of the spent 75 gases into the exhaust chambers 15 communicating with the exhaust manifold 16, the valves 10 and 14 being normally held seated by the compression springs 17 in the usual manner.

The foregoing described parts are the 80 well known features of an ordinary internal combustion engine and I employ in combination therewith the demountable head 18 provided with the combustion chambers 19, communicating with the fuel chambers 20 85 and the exhaust chambers 21, communication between the combustion chambers 19 and the fuel chambers 20 being controlled by the intake valves 22 held normally seated 90 by the compression springs 23 surrounding the valve stems 24 of the intake valves 22 and interposed between heads 25 of the stems 24 and the upper surface of the demountable head 18, while the communication 95 between the combustion chambers 19 and the exhaust chambers 21 is controlled by the exhaust valves 26 held normally seated by the compression springs 27 surrounding the exhaust valve stems 28 and 100 interposed between the heads 29 of the exhaust valve stems and the upper surface of the demountable head 18.

The fuel charge enters the fuel chambers 20 through the ports 30 from an intake manifold operatively mounted at the opposite side of the motor and similar to the 105

intake manifold 12 but elevated to a plane above that of the intake manifold 12, while the spent gases in the exhaust chambers 21 pass outwardly through the ports 31 into an exhaust manifold also operatively positioned at the opposite side of the motor and similar to the exhaust manifold 16.

Suitably mounted upon the upper surface of the demountable head 18 are the posts or standards 32 provided with the journals or bearings 33 in which is mounted the cam shaft 34 provided with the intake valve operating cams 35 and the exhaust valve operating cams 36, and for operating the cam shaft 34 there is provided upon one of its ends the sprocket wheel 37, connected by the sprocket chain 38 to the sprocket wheel 39 secured upon the engine shaft 2 or upon one side of the fan belt pulley 3 as desired, the ratio of the revolution of the sprocket wheel 37 to the revolution of the sprocket wheel 39 being one to two so that the sprocket wheel 39 will make two revolutions to one of the sprocket wheel 37 in order to properly time the speed of the cam shaft 34.

In this method employed I preferably position the respective valves of the motor and the respective valves of the demountable head in vertical alignment with each other though I may position these valves in other relative positions.

Briefly describing the operation of the foregoing mechanisms, the cam shaft 6 of the motor and the cam shaft 34 of the demountable head are so operated and timed with respect to each other that an intake valve 10 of the motor will be elevated to admit fuel from a fuel chamber 11 of the motor into a combustion chamber 19 of the head, and simultaneously an intake valve 22 of the head will be depressed to admit fuel from a fuel chamber 20 of the head into the combustion chamber 19. After the explosion of a fuel charge an exhaust valve 14 of the motor will be elevated to allow the spent gases to escape from a combustion chamber 19 of the head into an exhaust chamber 15 of the motor, and simultaneously therewith an exhaust valve 26 of the head will be depressed for also allowing the spent gases to escape from a combustion chamber 19 into an exhaust chamber 21 of the head. This operation continues consecutively in the respective cylinders of the motor, and consequently each cylinder of the motor is supplied with two intake valves and two exhaust valves thereby increasing the efficiency of the motor.

In Fig. 2 of the drawings I disclose another method of attaining the results desired by my invention and the construction disclosed therein is similar to that shown in Fig. 1 excepting some of the detail parts wherein it will only be necessary to herein-
65 after describe the above mentioned detail

parts. In this instance I employ the lower cam shaft 40 provided with a plurality of similarly disposed pairs of cams 41, each pair of the cams 41 simultaneously actuates an intake valve 10 and an exhaust valve 14 of the motor so that all of these valves of the motor are transformed into a plurality of pairs of exhaust valves so that each of the cylinders is supplied with two exhaust valves which are consecutively elevated by 70 the pairs of cams 41 upon the cam shaft 40 so that the spent gases will pass from a combustion chamber 19 of the head into an exhaust chamber 15 and a fuel chamber 11 of the motor, the fuel chambers 11 of the motor being transformed into exhaust chambers by the employment of the cam shaft 40 and by removing the intake manifold 12 and covering the intake ports of the chambers 11 with a leg of the exhaust manifold 42, so that it is clearly shown that all of the original valves of the motor are now transformed into a plurality of pairs of exhaust valves.

Mounted in the standards 32 upon the demountable head 18 is the upper cam shaft 43 provided with a plurality of similarly disposed pairs of cams 44 which in this instance simultaneously depresses an intake valve 22 and an exhaust valve 26 of the head so as to admit fuel into a combustion chamber 19 of the head from the fuel chamber 45 which communicates by means of the ports 46 with an intake manifold (not shown) operatively positioned at the opposite side of the motor. The fuel chamber 45 in this instance is a single chamber in the upper portion of the head 18 and extends the full length thereof and, therefore, the exhaust chambers 21 of the head 18 of Fig. 1 are dispensed with. By the employment of the cam shaft 43 and its pairs of cams 44 all of the valves of the head are transformed into a plurality of pairs of intake valves which are operated in consecutive pairs during the operation of the motor. The cam shafts 40 and 43 are operated and timed in a similar manner to that in which the cam shafts 6 and 34 of Fig. 1 are operated, and it will be seen that each of the cylinders of the motor is also supplied with two intake valves and two exhaust valves by this method.

While I prefer to operate the upper cam shafts 34 and 43 through the medium of the sprocket wheels 37 and 39 and the connecting sprocket chain 38 I may employ bevel pinions in lieu of the sprocket wheels 37 and 39 and operatively connect the pinions with any suitable form of connecting shaft, or any other suitable driving connections between the motor shaft and the cam shafts.

I have endeavored to clearly and concisely set forth the novel features of my invention

and the advantageous results attained thereby in the foregoing illustrations and descriptions of the two methods which I employ and have adopted for this purpose, but it is 5 to be understood that I am not limited to these disclosures as my invention is capable of application to a wide range of motors and the unlimited use of the additional valves, requiring only such alterations in dimensions and conformations of the elements necessary to meet the requirements of the case.

By this invention I am enabled to increase the normal power curve of a motor to any practicable degree, and by the addition of 15 another cam shaft the variable valve timing is made possible. Again, should either the original valve mechanisms or the additional valve mechanisms become disabled, the operating mechanisms of the disabled set of 20 valves may be disconnected or one throttle closed and the motor may then be operated at its normal power.

Having described my invention, what I claim as new and desire to secure by Letters Patent, is:—

1. An internal combustion motor, comprising a cylinder block containing a plurality of cylinders, a removable unitary head for all of said cylinders, said head provided 30 with an intake and an exhaust valve for each cylinder and said cylinder block provided with an intake and an exhaust valve for each cylinder, intake and exhaust manifolds co-operating with the respective valves, and 35 means for operating said valves.

2. An internal combustion motor, comprising a cylinder block containing a plurality of cylinders, a removable unitary head for all of said cylinders, said cylinder block 40 provided with an intake and an exhaust valve for each cylinder, said head provided with an intake and an exhaust valve for each cylinder, intake and exhaust manifolds co-operating with the respective valves, and 45 means for operating the sets of valves conjunctively and also adapted to operate one set of valves without the other.

3. An internal combustion motor, comprising a cylinder block containing a plurality

of cylinders, a removable unitary head for 50 all of said cylinders, said cylinder block provided with an intake and an exhaust valve for each cylinder, said head provided with an intake and an exhaust valve for each cylinder, intake and exhaust manifolds 55 co-operating with the respective valves, and means for operating the valves of said cylinder block and the valves of said head conjunctively with each other and capable of arrangement for operating one set of the 60 valves without the other.

4. An internal combustion motor, comprising a cylinder block containing a plurality of cylinders, a removable unitary head for all of said cylinders, said cylinder block provided with an intake and an exhaust valve for each cylinder, said head provided with an intake and an exhaust valve for each cylinder, intake and exhaust manifolds co-operating with the respective valves, cam 70 shafts for operating said valves, and means for operatively connecting said cam shafts with the motor crank shaft.

5. An internal combustion motor, comprising a cylinder block containing a plurality of cylinders, a removable unitary head for all of said cylinders, said cylinder block provided with an intake and an exhaust 80 valve for each cylinder, said head provided with an intake and an exhaust valve for each cylinder, intake and exhaust manifolds co-operating with the respective valves, a cam shaft upon said cylinder block for operating the valves thereof, a cam shaft upon said head for operating the valves 85 thereof, and means for operatively and independently connecting said cam shafts with the motor crank shaft to operate the respective valves of said block and said head conjunctively with each other and to also operate one set of the valves without the other.

In testimony whereof I have signed my name to this specification in the presence of a subscribing witness.

JESSE D. LANGDON.
